UNITED STATES PATENT OFFICE.

STANLEY C. KEARNEY, OF WILKES-BARRE, PENNSYLVANIA.

WHIP-LOCK.

1,107,617.

Specification of Letters Patent. Patented Aug. 18, 1914.

Application filed January 5, 1914. Serial No. 810,443.

To all whom it may concern:

Be it known that I, STANLEY C. KEARNEY, a citizen of the United States, residing at Wilkes-Barre, in the county of Luzerne, 5 State of Pennsylvania, have invented certain new and useful Improvements in Whip-Locks; and I do hereby declare the following to be a full, clear, and exact description of the invention, such as will enable others 10 skilled in the art to which it appertains to make and use the same.

The present invention is directed to improvements in whip locks, and has for its object to so construct a device of this character 15 that the whip can be easily and quickly locked in the socket.

A further object of the invention is to provide a whip socket with a simple form of lock so as to prevent removal of the whip 20 from the socket by an unauthorized person.

With these and other objects in view, this invention resides in the novel features of construction, formation, combination and arrangement of parts to be hereinafter more 25 fully described, claimed and illustrated in the accompanying drawing, in which:—

Figure 1 is a front elevation of the device. Fig. 2 is a vertical central sectional view 30 through the device. Fig. 3 is a sectional view on the line 3—3 of Fig. 1. Fig. 4 is a detail perspective view of the locking device, removed from the socket.

Referring to the drawing the numeral 1 designates a socket of the conventional form, 35 the same being attached to the dash board of the vehicle in the usual manner.

A split band 2 is provided, and consists of sections 3 and 4, the same being curved to conform to the curvature of the socket 1, 40 said sections being hingedly connected at one of their ends, as indicated at 5. The section 4 has its free end provided with a lock casing 6, the locking mechanism contained therein being of any well known 45 form, and adapted to coöperate with the shackle 7 carried by the free end of the section 3. The shackle 7 may be readily unlocked upon inserting a key in the key-hole 8. The sections 3 and 4 are each provided

with horizontally disposed webs 9, the same 50 being formed integral with the upper edges of said sections and have their inner edges curved so as to conform to the curvature of the annular groove 10 carried by the sleeve 11, said sleeve being fixed in any suitable 55 manner to the whip butt 12. The section 4 is riveted or otherwise suitably secured to the upper end of the socket 1, and in a position so that the web 9 thereof engages over the upper edge of the socket so as to conveniently engage the annular groove 10 of the sleeve 11, it being of course understood that the web 9 of the section 3 also engages said groove, and when the shackle 7 is locked in the casing 6 it is obvious that the removal 60 of the whip from the socket is positively prevented. It will be noted that the section 3, being hingedly connected to the section 4 may be readily swung outwardly so that the web thereof will disengage the groove 10, 70 whereupon the whip may be removed.

From the foregoing description it will be apparent that a lock for whips has been provided which may be easily and quickly applied to a socket of the conventional form. 75

The section 3 is provided with a pin 13, which is adapted to engage the perforation 14 formed in the socket 1, and when engaged thus the section 3 will be firmly secured.

What is claimed is:—

The combination with a whip socket, of a whip engageable therein, a sleeve carried by the whip and having an annular groove therein, a sectional band, one of said sections being fixed to the socket and the other being 85 free to swing toward or away from the socket, said sections having webs formed integral with their upper edges for engaging said groove when the free ends of the sections are interlocked and means for positively locking the sections together. 90

In testimony whereof, I affix my signature, in the presence of two witnesses.

STANLEY C. KEARNEY.

Witnesses:
